UNITED STATES PATENT OFFICE

PAUL W. BAKER, OF ST. LOUIS, MISSOURI, ASSIGNOR TO WAGNER ELECTRIC CORPORATION, OF ST. LOUIS, MISSOURI, A CORPORATION OF DELAWARE

BRUSH HOLDER

Application filed January 26, 1929. Serial No. 335,165.

My invention relates to a brush holder and associated means for actuating the brushes carried thereby. While it is applicable to machines having any form of commutator, it is particularly advantageous for use in machines having a commutator whose contact surface is at right angles to the axis of the rotor.

In motors for certain kinds of service, such as operating refrigerating devices and other apparatus in the household, it is highly desirable that no noise of any kind be produced during the starting and stopping of the machine, nor during normal operation, and one source of noise in prior machines has been the "chattering" of the brushes due to the vibration of the brushes against the walls of the brush holder slots, which vibration is produced by the irregularities of the commutator surface, and in machines having a vertical face commutator the slight longitudinal reciprocations of the rotor cause added brush motion. Inequality of brush pressure on the commutator is also a source of noise.

One of the objects of my invention is to overcome brush noise due to "chattering," and another object is to provide means for applying and maintaining equal pressure on the brushes. Also, my invention has the advantage of reducing the number of brush advancing springs which have heretofore been employed.

In the accompanying drawings, Figure 1 is a top plan view of a brush holder and associated parts embodying my invention; Figure 2 shows a cross section of the holder along the line 2-2' of Figure 1, and in addition thereto its relation to the commutator and other parts of a well known type of single phase motor having a vertical face commutator and provided with centrifugal means for moving the brushes out of contact with the commutator after the motor has been started; and Figure 3 diagrammatically illustrates a side view of a pair of brushes and guides therefor, and illustrates brush advancing means and its relation to the brushes whereby the objects of my invention are secured.

The brush holder comprises a casting 1 having radially extending arms 2, which are provided with brush guides formed by longitudinal slots in the arms and slot closing plates 3, and, as to the features just mentioned, is constructed in the manner described in Evans Patent No. 1,354,899 issued October 5, 1920.

The holder illustrated in Figure 1 is for a machine requiring two pairs of brushes and is provided with integral studs 4 centrally positioned between the guides for the brushes of each pair. Springs 5 coiled at the center are mounted on these studs and have one end of the wire from which they are formed extended to bear upon a brush at one side of the stud and the other end extended to bear upon the brush at the other side of the stud. The ends of the springs thus apply an advancing pressure to the brushes to maintain them in contact with the commutator and it will be noted that the result of the construction described is that the pressure applied to each of the brushes actuated by the ends of a particular spring will necessarily be equal, since each brush forms a fulcrum for the application of the spring pressure to the other brush.

In order to prevent "chattering" of the brushes I apply the brush advancing pressure at an angle to the direction of advance, as indicated by the arrows in Figure 3, and thereby hold the brush in pressure engagement with a part or parts of the walls of the brush guide and thus prevent lateral brush vibration and the consequent noise usually referred to as "chattering."

The mechanism shown in Figure 2 for mounting and actuating the brush holder being of well known construction need not be more than generally described. The holder is mounted on a circular extension 6 of the end plate 7 of the motor. The holder is actuated into operative relation with the commutator 8 by means of the spring 9 on the motor shaft 10, and is moved out of operative relation by means of collar 11 actuated by the rods 12 which are connected to the centrifugal mechanism (not shown). In the running position the commutator is short-circ-

cuated by a plurality of short-circuiting plates 14 carried by the collar 11.

As shown in Figures 1 and 2, the walls of the brush guides are provided with slots 13 whereby the brush advancing spring ends may continue to bear on the brushes until they are shortened by wear to a predetermined degree.

In a particular motor certain brush pressures cause less noise than others and it is desirable to select the pressure producing the least. Means for equalization of brush pressure has the advantage that adjustment of one spring establishes the desired pressure on two brushes and maintains it.

It will be apparent that my invention has the advantage of conveniently and cheaply securing equality of brush pressures and elimination of brush chattering.

Having fully described my invention, what I claim as new and desire to secure by Letters Patent of the United States is:

1. In a dynamo electric machine, the combination with a brush holder provided with brush guide slots and brushes therein, of a resilient brush follower having one end bearing on one of a pair of brushes and the other end bearing on the other brush, and a pivot support for said follower intermediate its ends whereby the pressure on one brush will be proportional to the pressure on the other brush.

2. The combination of a brush holder for dynamo electric machines having extending arms provided with brush guide slots and having a stud projecting between said arms, brushes in said slots, and a brush follower of spring material coiled intermediate its ends and having one end bearing upon one brush and the other bearing upon the other brush, said coil portion being pivotally mounted on said stud.

3. In a dynamo electric machine, a brush holder comprising a hub having two radially extending arms provided with brush carrying slots and having a radially extending stud centrally positioned between the arms, brushes in said slots, a resilient member pivoted on the stud and having one of its ends arranged to apply advancing pressure to the brush on one side of the stud and its other end to apply advancing pressure to the brush on the opposite side of the stud, whereby a substantially equal pressure will be applied to each brush.

4. In a dynamo electric machine, the combination of two commutator brushes, means forming guides therefor, a pivot, a resilient member rotatably mounted on said pivot and having one of its ends arranged to apply advancing pressure to one brush and the other end to apply advancing pressure to the other brush, each end being also adapted to apply its pressure to its brush in such direction as to tend to maintain the brush in lateral

contact with its guide, the pivot of the resilient member being also so located that the total pressures applied by it to each brush will be equal.

In testimony whereof, I hereunto affix my signature, this 22nd day of January, 1929.

PAUL W. BAKER.
